UNITED STATES PATENT OFFICE.

SETH GOODHUE, OF WILMOT, NEW HAMPSHIRE.

TRAMWAY-SWITCH.

SPECIFICATION forming part of Letters Patent No. 451,760, dated May 5, 1891.

Application filed April 1, 1890. Serial No. 346,178. (No model.)

To all whom it may concern:

Be it known that I, SETH GOODHUE, a citizen of the United States, residing in Wilmot, Merrimac county, New Hampshire, have invented certain new and useful Improvements in Tramway-Switches, of which the following is a specification.

This invention relates to switches for horse-railways, electric railways, and other tram-lines, so constructed as to enable the driver of a car to throw the switch as he approaches it, through the medium of instrumentalities on the car and track, and without the necessity of either stopping the car or leaving it. Switches of this character have the switch-tongue connected to the transversely-movable cam projecting from the road-bed and acted upon by one or more movable projections on the car controlled by a treadle or treadles or other operating device under the control of the driver. To turn in one direction the driver throws down one of the projections sufficiently to bring it into engagement with the transversely-movable cam on the track to throw the switch to the side desired.

My invention provides an improved construction for this purpose, which will be fully hereinafter described.

Figure 1 of the accompanying drawings is a plan of a tramway-track provided with a switch constructed according to my invention and showing the wheels and the shoe-plungers of a car approaching the switch. Fig. 2 is a vertical longitudinal section of the track and car on the line 2 2 in Fig. 1. Fig. 3 is a vertical transverse section in the planes denoted by the lines 3 3 in Fig. 2. Fig. 4 is a half plan similar to Fig. 1, but showing the act of locking the switch-tongue by the flange of the wheel before the disengagement of the cam projection by the shoe. Fig. 5 is a fragmentary transverse section on the line 5 5 in Fig. 1, on a larger scale. Fig. 6 is a transverse section on the line 6 6 in Fig. 1, on a larger scale. Fig. 7 is a plan of the base-plate of the switch removed.

Let A A designate the track-rails of the main and branching tracks, B the switch-tongue, and C C' the respective cast-metal frogs or base-plates such as are commonly used with tongue-switches for tramway-tracks. The base-plate D (shown separately

in Fig. 7) is fastened between the rails, the opposite ends *aa* of its transverse portion being fastened by bolting, riveting, or otherwise to the frogs C C'. The portion of the plate extending transversely of the track is trough-shaped, as shown in the transverse section, Fig. 6, forming a guideway *b* for a transverse slide E. This slide consists of a plate mounted to slide freely in this trough-shaped guideway and connected at one end by a pivot-pin *c* to a projection *d*, formed integrally with or fastened to the tongue B, and which projects laterally from it in the manner best shown in Fig. 3. On the middle of the slide is formed a cam projection *e*, which stands above the top of the trough-shaped guide *b* and overlaps the latter, as shown in Figs. 1 and 2. The opposite end portions of the slide are fastened down and protected by cap-plates F F, having external flanges, as best shown in Figs. 1 and 6. The ends of these cap-plates approaching the middle of the track are formed as straight shoulders *f*, between which the cam projection *e* may play. When the switch is thrown to either side, the cam projection *e* is nearer to one shoulder *f* than to the other.

The base-plate D is formed with flat wings 80 or extensions D' and D'', projecting from it in direction longitudinally of the track on the approaching and receding sides, respectively, of the trough-shaped guideway *b*. These plates are formed with their upper surfaces 85 very slightly inclined, rising toward their junction with the transverse portion, and joining the latter with their upper surfaces flush with the upper surfaces of the sides of the trough-shaped guides *b* and with the top surface of the plate E.

The car G is provided with two vertical frames H H', in which slide vertically plungers J J', the lower ends of which carry cam-like shoes K K', the shape of which in plan 95 is shown in Fig. 1. These plungers are pressed up by springs L L', respectively. On the front platform of the car are provided two treadles M and M' in convenient position to be depressed by the foot of the driver. The 100 plungers of these treadles are connected with the arms m m', respectively, of two levers N N', the middle portions of which constitute rock-shafts hung in bearings p p underneath

the car, their axes extending longitudinally thereof. The rear ends of these levers are formed with arms $n\ n'$, the end portions of which engage the plungers $J\ J'$, respectively, 5 by entering slots in the upper ends thereof, as shown, or by any other convenient connection. In pressing down either treadle the corresponding lever N or N' is vibrated, thereby communicating movement to the corresponding plunger J or J' and pressing down its cam-shoe K or K' . As shown in Figs. 2 and 3, these cam-shoes stand normally above the level of the cam projection e , so that when not pressed down they can pass freely 10 over this cam projection. It will also be seen from Fig. 3 that the outer sides of the cam-shoes stand in the same vertical longitudinal planes as the shoulders $f\ f'$, or approximately so, and that each of the cam-shoes is of the 15 same width as the space between the cam projection e and the shoulder f , from which it is at the time the farthest removed. Thus if the left hand cam-shoe K in Fig. 3 were pressed down it would simply pass freely 20 through the space k intervening between the left-hand shoulder f and the cam projection e without having any effect upon the switch. 25

In order to operate the switch, the driver will press down the treadle on the side toward which he wishes the car to turn—that is, if the car is to be switched to the left hand of the two tracks ahead he will depress the left treadle M' . He should do this just as the shoes come over the plate-extension D' , so that 30 the shoe K' , which is pressed down, will ride along on this plate-extension, and be guided thereby against any vertical movements due to the rocking of the car. To facilitate its movement over the plate, the shoe is provided 35 with an anti-friction roller l , which rolls against the surface of the plate. The shoe thus enters into the narrower space k' between the cam projection e and the nearer shoulder f , and, being wider than this space, in wedging 40 itself through it it forces the cam projection e toward the opposite side, thus sliding the plate E and throwing over the switch-tongue B . By reason of the parallel side surfaces of the shoe and the projection e the 45 50 sliding plate and switch-tongue are held stationary for an instant before being released by the passage of the shoe beyond the projection, and during this instant the flange of the car-wheel P enters against the tongue, so that 55 any return movement of the latter due to a rebound or other cause is prevented, and the switch is locked fast until this wheel has passed and the car has been thereby directed onto the proper track. As soon as the 60 switch has been thus thrown, the driver may release the treadle, whereupon the shoe will rise to its former position. The plate-extension D' is designed to form a smooth guiding-surface, over which the shoe may travel after 65 clearing the cam projection e and before the driver releases it.

In order to prevent the clogging of the switch-tongue B by dirt which may work into the grooves of the frog C , I construct the latter with lateral holes or openings $q\ q'$ at intervals, as denoted by the dotted lines in Fig. 1, 70 passing beneath the rail, as shown more clearly in Figs. 3 and 5. I also provide the inner flange of the frog with similar holes or openings q' . Any dirt, water, or ice which may 75 enter the groove or space within which the switch-tongue plays will thus be led to readily work out through these openings without interfering with the free movement of the switch-tongue. 80

My invention provides a very simple and inexpensive construction of automatic tramway-switch involving the minimum of mechanical devices or moving parts on the road-bed, and one which operates with great certainty in throwing the switch and requires no extreme nicety of construction or adjustment of working parts of the road-bed or on the respective cars. 85

The operation of the switch by a wedging 90 or cam shoe entering between a fixed shoulder on one side and a movable cam projection on the other, and by wedging itself through the space thus formed displaces the cam projection until the space becomes wide enough to 95 admit its passage, is a characteristic feature of my invention. To this construction is due the advantage of the avoidance of all lateral strain upon the cam-shoe, this strain being taken up by the lateral shoulder f . 100

The automatic locking of the switch-tongue by the flange of the wheel I regard as an important feature of my invention. To accomplish this result the cam-shoes $K\ K'$ are arranged at so short a distance in advance of 105 the first pair of wheels relatively to the distance of the cam projection e in advance of the end of the switch-tongue that the respective cam-surfaces will come into contact and cease to act upon each other the 110 instant before the wheel-flange encounters the end of the tongue, and the respective parallel surfaces of the cams are sufficiently prolonged to remain in engagement until after the wheel-flange has passed into engagement with the tongue. The provision 115 of the plate-extension D' , I also consider an important feature, inasmuch as it avoids the difficulty which would otherwise arise by reason of the longitudinal rocking or teetering of 120 the car or the varying height of the car above both rails, depending upon whether the car is lightly or heavily laden. In either case the cam-shoe K or K' is pressed down until it strikes the plate-extension D' , which thus 125 forms the bottom guide for the shoe, the latter being held against the surface of the plate by the yielding pressure of the driver's foot. The correct engagement of the shoe with the shoulders f and cam projection e is thus insured, and all liability of the shoe either 130 jumping over the switch-operating cam or

abruptly colliding with the transverse guideways is avoided.

I claim as my invention the following defined novel features, substantially as hereinbefore specified, namely:

1. The combination, with a railway track and switch, of a plate fastened transversely between the track-rails and formed with a trough-like guideway, a slide mounted to move in said guideway, connected to the switch-tongue, and formed with a cam projection, and cover-plates fastened to said transverse plate to confine said slide in the guideway and constructed at their ends to form reinforcing shoulders on opposite sides of the cam projection.

2. The combination, with a railway track and switch having a transversely-movable slide connected to the switch-tongue and formed with a cam projection, of a car, vertical plunger-frames $H H'$ carried thereby, plungers $J J'$, working in said frames, cam-shoes $K K'$, mounted at the bottoms of said plungers and adapted for engagement with said cam projection, treadles $M M'$, and levers $N N'$ for communicating motion from said treadles to the respective plungers, arranged on longitudinal axes, and having arms $m m'$

engaging the respective treadles and $n n'$ engaging the respective plungers.

3. The combination, with a railway track and switch having a transverse guideway, a slide mounted to move in said guideway, connected to the switch-tongue, and formed with a cam projection, a guiding-plate D' on the approaching side of the switch, extending longitudinally of the track, ascending in an incline from the level of the pavement, and terminating in the same plane as the top of the slide, of a car, a vertically-movable cam-shoe carried by said car, normally elevated sufficiently to pass over said cam projection and adapted when depressed to engage therewith and thrust it laterally, a treadle or equivalent means for communicating motion to said cam-shoe to force it down, and an anti-friction roller on the under side of said cam-shoe to enable it to ride against the surface of said longitudinal plate.

In witness whereof I have hereunto signed my name in the presence of two subscribing witnesses.

SETH GOODHUE.
